UNITED STATES PATENT OFFICE.

GEORGE C. DAVIS, OF CHICAGO, ILLINOIS, ASSIGNOR TO G. M. DAVIS REGULATOR COMPANY, OF CHICAGO, ILLINOIS, A CORPORATION OF ILLINOIS.

NONRETURN VALVE.

Application filed July 10, 1926. Serial No. 121,665.

My invention relates to improvements in check or non-return valves particularly for gas or air lines and the like and has for one object to provide a new and improved type 5 of the well-known non-return valve wherein the parts will be delicate and sensitive, offer a minimum resistance to flow in one direction, make a positive closure in the reverse direction and wherein the floating 10 valve members may be adjusted, replaced and manipulated with a minimum of difficulty and complication. Other objects will appear from time to time throughout the specification and claims.

15 My invention is illustrated more or less diagrammatically in the accompanying drawings, wherein—

Figure 1 is a side elevation of the valve;

Figure 2 is a section along the line 2—2 20 of Figure 1.

Figure 3 is a section along the line 3—3 of Figure 1.

Like parts are indicated by like characters throughout the specification and drawings.

25 A is the valve casing; A¹ the intake and A² the discharge pipe so that gas or air flows through the valve in the direction shown by the arrow. The underside of the 30 housing is bounded by a curved wall as at A³; the upper side which is open terminates in a flange A⁴ extending clear across the area of the valve. A⁵ is an extension housing adapted to be bolted to the flange A⁴ and 35 closed by the cap A⁶.

The inside of the housing is flanged as at B. Resting on this flange and held seated thereon by means of the set screws B¹ B² are a plurality of grid members B² B² extending across the effective opening of the 40 valve. Spaced beyond the down-stream side of these grid members on the down-stream side thereof is a bridge B³ held in place by the studs B⁴.

45 C C are valve plates of such width as to bridge the gap between adjacent grid members. These plates are bolted at two points as at C¹ C¹ to the lug C², on the underside of the cap A⁶ and extend down through the 50 housing A⁵ into the valve housing A and are adapted to lie along the grid members, the length of the plates C being such as to extend beyond the lower end of the grid members as indicated at C³ C⁴. The bridge B³ 55 limits the forward movement of the valve

plates in the direction of flow of the gas so as to maintain them in proper working relation with the grid. If the flow of gas is reversed, these feathers or plates are thrown back against the grid and close the 60 valve. The valve plates are thus removable as a unit with the cap A⁶ and the grid members tied together as they are by the peripheral ring B⁵ are also removable as a unit from the housing by release of the set screws 65 B¹ so that both the grid and the plate may be easily removed for repair, renewal or change. The long housing through which the plates extend upwardly away from the grid permits of these plates being long 70 enough so that the flexure or bending of the plates is on such a long arc that crystallization and breakage is reduced to a minimum. The two point attachment of these plates makes it possible to anchor them rigidly 75 at one end and without the use of any additional guiding or positioning means other than the bridge which prevents their being driven too far and permits their being held permanently in proper working position. 80

The valve plates or feathers are preferably of spring steel plated with cadmium or other suitable wear and corrosion resisting material. Since the plates are long and flexible there is not sufficient bending of the 85 plate to cause any appreciable distortion of the plate or of the protective coating associated with it.

It will be evident that while I have shown in my drawings an operative device, still 90 many changes might be made in the size, shape, arrangement and disposition of parts without departing materially from the spirit of my invention and I wish, therefore, that my showing be taken as in a sense diagrammatic. 95

I claim:

1. In a non-return valve, a housing open at one side in a direction at right angles to the line of flow, a grid contained within the 100 housing in the line of flow, a closure for the open side of the housing, a flexible valve plate rigidly mounted on the closure and extending through the housing and overlying the grid. 105

2. A non-return valve comprising a housing, a removable grid plate therein having a plurality of grid bars extending across the line of flow, a seat for the plate, means accessible from the outside of the housing 110

for locking the grid plate on its seat, the housing being open along one side, an extension housing in line with the opening, a closure therefor, a plurality of flexible 5 valve plates rigidly mounted on the closure extending through the extension housing, across the valve housing and adapted to lie alongside of and close the space between the grid bars, means on the down-stream side 10 of the grid plate comprising a fixed bridge for limiting the down-stream movement of the plates.

3. A non-return valve comprising a housing, a grid plate therein, having a plurality 15 of grid bars extending across the line of flow, the housing being open along one side, a closure for the open side, a plurality of flexible valve plates, rigidly mounted on the closure extending across the valve housing 20 and adapted to lie alongside of and close the space between the grid bars, means normally out of contact with the plates for limiting their down-stream movement, said means comprising a bridge extending across the 25 line of flow perpendicular to the grid bars on the down-stream side thereof.

4. A non-return valve comprising a housing, a grid plate therein, having a plurality of grid bars extending across the line of flow, the housing being open along one side, a closure for the open side, a plurality of 30 flexible valve plates rigidly mounted on the closure extending across the valve housing and adapted to lie alongside of and close

the space between the grid bars, the valve 35 plates being substantially longer than the effective opening closed by them whereby their point of rigid attachment is far removed from the grid plates.

5. A non-return valve comprising a housing, a grid therein, having a plurality of grid bars extending across the line of flow, a chamber extending laterally from one side of the housing and open thereto, and located in the same general plane as the grid, a plurality of flexible valve plates anchored in the chamber at a point far removed from the housing, held by their anchorage against movement in the plane of the grid, but free to move transversely toward and from the 50 grid to open and close the spaces between the grid bars, and means separate from the plates for limiting their down stream movement.

6. A non-return valve comprising a valve 55 seat comprising a plurality of parallel grid bars, a plurality of valve shoes adapted to engage said bars and close the spaces between them, elongated flexible valve supporting members carrying the shoes and 60 anchored at points removed from the valve seat, a housing extending laterally away from the valve seat and enclosing said flexible members, and a cover for said housing upon which the members are anchored. 65

Signed at Chicago, county of Cook, and State of Illinois, this 7th day of July, 1926.

GEORGE C. DAVIS.
